UNITED STATES PATENT OFFICE.

JESSE E. HODGES, OF COVINGTON, KENTUCKY.

ADJUSTABLE STRUT.

1,385,546.

Specification of Letters Patent. Patented July 26, 1921.

Application filed December 8, 1916. Serial No. 135,776.

To all whom it may concern:

Be it known that I, JESSE E. Hodges, a citizen of the United States, and a resident of Covington, in the county of Kenton and State of Kentucky, have invented certain new and useful Improvements in Adjustable Struts, of which the following is a full, clear, and exact description, reference being had to the accompanying drawing, forming part of this specification.

This invention has relation to adjustable struts for supporting concrete forms in the construction of buildings. In devices of this nature the great weight which must be supported and the danger attendant upon the falling or slipping of the work as well as the damage caused by a fall demands very special construction of strut to permit of its being adjustable.

While it may be contested that a mere clamping strut is perfectly safe for supporting temporary concrete work, still many public building departments will not allow their use as they contend that imperfect assembly of them will result in a slipping of the devices, and hence large damages and danger to concrete workers and others at work on buildings. As a usual practice in the use of clamping adjustable struts, a compensating device such as a wedge or the like has often to be used to take up the slippage of the strut.

The object of this invention is to produce an adjustable strut which is drawn together with a clamping device and when drawn together has a lock, which will cause the supported weight to force the clamp into tighter position to prevent slipping.

This object and other advantages to be noted I accomplish by that certain construction and arrangement of parts to be hereininafter more specifically pointed out and claimed.

In the drawing,

Fig. 1 is a side elevation of my novel clamp lock strut in use.

Fig. 2 is a detail section through the locking member, showing a portion of the strut in side elevation.

Fig. 3 is a perspective view of a locking member of slightly different shape.

Fig. 4 is a perspective view of the lock member shown in Figs. 1 and 2.

The adjustable strut shown consists in a central supporting column or standard 1, on each side of which are side supports 2, 2^a.

The standard 1 rests on the floor of the building or other strut supporting surface, and the side standards connected at the top by means of a block 3 support the concrete workers' forms as at 4, or other weight to be supported.

In usual practice, I have found it well to clamp the side members to the central standard above the ends of the side members by means of a U-shaped strap 5 which pivots at its open end a cam 6. By driving this cam downwardly after slipping the strap up over the members 1 and 2, 2^a, they will be clamped firmly together, but not sufficiently to prevent slipping under unusual conditions. This upper clamp is not a requisite, but I have found it valuable to prevent spreading of the side supports, as well as to give further security.

The side support 2^a is cut shorter than the side support 2, to permit of a clamping of the one support against the central column and the locating of the locking clamp beneath the end of the other. Two stout metal plates or straps 7 are provided, connected at one end by the bolt 8 and at the other by the bolt 9 so as to completely surround the column. On the bolt 9 is secured the clamp 10, which has a suitable cam face such that when it is driven down by a hammer the face will come into constantly closer contact with any member inside of the straps or plates.

On the bolt 8 is mounted a clamp lock 11, which has a curved roughened face 12, which is adjacent the bolt holes 13 in the clamp lock. The bolt holes are set so that the face 12 is eccentric to them, or else the curved face can be made in the shape of a cam also. The clamp lock extends upwardly from the bolt holes for a considerable distance and is thus set so that pressure on the upper end thereof as at 14 will tend to force the roughened surface to swing inwardly against any member between the straps.

For convenience, the clamp lock is provided with a slot or slots 15 through which passes a bolt 16. An angle plate 17 is provided which is adapted to be merely set, or if desired screwed onto the end of the strut 2^a and in the corner of this angle plate is located the head of the bolt so that the lock is held against falling away from the corner or angle plate. The clamp locks thus have the curved surface meeting the flat surface 18 which extends up to the angle plate and

the holes 13 for the pivot bolts are at the apex of the flat and the curved surfaces.

In using the device, which is set over the central column when the strut is being put up, the plates or straps are moved up until they lie in a position along the end of the side support 2 and just beneath the end of the side support 2^a. The angle plate is then screwed or placed to the member 2^a, and the cam clamp 10 is driven downwardly with a sledge or the like.

As shown in Figs. 1 and 2, the driving of the cam down forces the clamp lock into a position with its roughened face against the central standard, and with its upper edge forced up against the angle plate. In this position, any weight or force applied downwardly on the standard 2^a will tend to force the lock more firmly into place and also to draw the cam clamp more firmly into place. There is therefore the possibility of adjustments by regulating the relation of the side supports and the central support or column and the positive locking of the parts in place by the driving down of the cam clamp.

In the showing in Figs. 3 and 4, the difference is that the clamp lock in one instance has a central web 20 (Fig. 3) and two slots 30 for the securing bolts to the angle plate for the short side standard. In another instance there is no central web and there is but one slot 15 (Fig. 4). The two clamp locks are otherwise the same except for the greater width of the showing in Fig. 3 for the curved and roughened surface, the said showing being such that the part can be made of lighter metal than the one shown in Fig. 4, thereby gaining a small saving in cost of production.

It is practical to dispense with the cam clamp in this device and use two clamp locks instead. No such showing is illustrated,

but it will be understood that with two clamp locks the device would have to be 45 driven up into place as shown in Fig. 1, whereupon the clamp locks would remain fixed as soon as downward pressure was applied on the side supports.

This is not the preferred form of my invention, because it is much less convenient to use, and has more chance of being improperly installed with the resultant dangers from slipping or dislodgment of the parts.

The preferred embodiment as illustrated 55 and above described is easy to install and fool-proof to a very high degree, as the only way the device can be set in place at all is the proper place, and the mere driving down of the cam clamp brings the parts into locking position.

Having thus described my invention, what I claim as new and desire to secure by Letters Patent, is:—

In an adjustable strut, the combination 65 with a central standard and side supports lying along the sides thereof, one of the side supports being shorter than the other, a frame surrounding the standard, a cam clamp pivotally mounted at one end of the 70 frame, and a clamp lock pivotally mounted at the other end of the frame, with said frame located horizontally on the standards, with the cam clamp in a position to engage the longer side support and force it against 75 the central standard, and the clamp lock to engage the under side of the short side support and the side of the central standard with a U-shaped clamp provided with a cam to engage and press the side supports together, located above the lower ends of the side supports, to hold the side supports temporarily prior to adjustment of the lower support, for the purpose described.

JESSE E. HODGES.
